WILLIAM A. LORENZ, OF HARTFORD, CONNECTICUT.

NOISELESS BUFFER FOR TYPE-WRITER ESCAPEMENT.

1,250,756.

Specification of Letters Patent. Patented Dec. 18, 1917.

Application filed January 31, 1917. Serial No. 145,579.

To all whom it may concern:

Be it known that I, NILS H. ANDERSON, a citizen of the United States, residing at Bridgeport, in the county of Fairfield and 5 State of Connecticut, have invented a new and useful Improvement in Noiseless Buffers for Type-Writer Escapements, of which the following is a specification.

The paper carriage of a typewriting machine is drawn across the frame by a spring tension device with a step by step movement as the space bar or the type or tabulator keys are operated in writing,—an escapement mechanism releasing and then stopping the 15 carriage after it has moved the required distance. This invention relates to the escapement mechanism provided for this purpose.

The paper carriage has a feed rack that is engaged by a pinion which is connected with 20 a toothed escape wheel. Through such connection the escape wheel is subject to the pull of the spring tension device provided for feeding the carriage and consequently tends to turn. Oscillatory feed and stop pawls 25 are arranged to disengage and engage the teeth of the escape wheel as the machine is operated for releasing the escape wheel and allowing the carriage to feed and for holding the escape wheel and stopping the carriage after it has fed. In machines in common use the carriage as it steps from tooth to tooth moves quickly and stops suddenly and this sudden arresting of the momentum 30 of the carriage causes considerable shock 35 and objectionable noise. The object of this invention is to provide a buffer for the stop pawl that is constructed and arranged to materially lessen the shock of the blows of the teeth of the escape wheel against the 40 stop pawl and arrest the movement of the carriage less suddenly when it feeds, which buffer is so designed that it can be conveniently attached to the present commercial machines without requiring any change in 45 the escape mechanism of such machines and can be used as a speed adjuster.

The invention is illustrated as applied to the well known "Underwood" typewriting machine, although it is applicable to other 50 makes of machines. Figure 1 shows a rear elevation, with parts broken away, of such a machine with a noiseless buffer that embodies the invention applied to the escape mechanism. Fig. 2 shows on larger scale an 55 elevation of the escapement rocker which

carries the feed and stop pawls and to which the noiseless buffer is shown as attached. Fig. 3 is an edge view of the rocker, pawls and buffer. Fig. 4 is a perspective view of the buffer.

In the type of machine shown the paper carriage 1 is drawn across the frame 2 in the direction indicated by the arrow 3 by the usual spring barrel 4 that is connected with the carriage by the band 5. Attached 65 to the underside of the carriage is the feed rack 6 that normally engages with the pinion 7. Connected with the pinion is the escape wheel 8. The free end of the stop pawl 9 normally engages a tooth of the escape wheel and holds the wheel against rotation. The stop pawl is pivoted to the escapement rocker 10 which is pivotally mounted on the ends of screw pintles 11 that turn in the stationary uprights 12. On the 70 upper end of the escapement rocker is a feed pawl 13. A spring 14 tends to draw the stop pawl forward and a fixed stop 15 is provided to limit the backward movement of the stop pawl.

When in the course of use of the machine the type keys or space bar are operated the escapement rocker is oscillated to first swing the feed pawl sidewise into the path of a tooth of the escape wheel and swing 85 the stop pawl sidewise out of engagement with the tooth of the escape wheel, then the stop pawl which has been drawn forward by its spring swings sidewise into the path of the next tooth of the escape wheel and the 90 feed pawl swings sidewise out of engagement with the tooth of the escape wheel and allows the wheel to turn and the carriage to feed one space. The blows of the teeth against the stop pawl when the escape wheel 95 turns drive the stop pawl, in the present machines, back against a fixed stop. To eliminate the shock and noise incident to this violent stopping of the carriage, a yielding buffer member is mounted on the escapement rocker in position to cushion the stop pawl when it is driven back. This buffer is shown as formed of a plate 16 with a slotted hole 17 for one attachment screw and a slotted notch 18 for another attachment 105 screw. A long slot 19 is cut in this plate so as to form an extended spring arm 20. This plate is attached to the escapement rocker in such position that the free end of the spring arm will engage the edge of the stop pawl 110

and will yield sufficiently as the pawl is thrown back by the turning of the escape wheel when the carriage moves to relieve the shock and eliminate the noise and the sudden stopping of the carriage. The slots in the buffer plate permit its adjustment up and down so that the spring buffer can be utilized to alter the time of starting of the carriage.

10 When the buffer is located at its lowest position the stop pawl is retained in such relation that the carriage will not be released until after a type has imprinted its impression on the paper. When the buffer is adjusted to its highest position the stop pawl is retained in such relation that the carriage will be released just previous to the type striking the paper. By setting the buffer in an intermediate position an intermediate 20 release may be obtained. Previously this adjustment, which is made according to the proficiency of the operator, has been effected by the use of what is known as a "speed spacer." Besides acting to eliminate noise and shock my improved buffer eliminates the use of a "speed spacer."

The invention claimed is;

1. The combination in a typewriting machine escapement, of an escapement rocker, a feed pawl carried by said rocker, a stop pawl pivoted on said rocker, and a plate having a resilient arm with its free end adapted to be engaged by the stop pawl

during its backward movement, adjustably attached to said rocker.

2. The combination in a typewriting machine escapement, of an escapement rocker, a feed pawl carried by said rocker, a stop pawl pivoted on said rocker, and a slotted plate having a yielding arm with its free end adapted to be engaged by the stop pawl during its backward movement, adjustably attached to said rocker so the point of engagement of arm and pawl may be varied.

3. The combination in a typewriting machine escapement, of an escapement rocker, a feed pawl carried by said rocker, a stop pawl pivoted on said rocker, and a plate attached to said rocker, said plate having an elongated slot formed therein to provide a yielding arm with its free end adapted to be engaged by the stop pawl during its backward movement.

4. The combination in a typewriting machine escapement, of an escapement rocker, a feed pawl carried by said rocker, a stop pawl pivoted on said rocker, and a plate attached to said rocker, said plate having an elongated slot formed therein to provide a yielding arm with its free end adapted to be engaged by the stop pawl during its backward movement, said plate also being slotted so it may be adjusted to vary the point of engagement of the arm and pawl.
